PORTABLE WELDING TRANSFORMER

Bert Fritiof Esbjorn Frelin, Västerås, Sweden, assignor to
Elektriska Sverksaktiebolaget, Göteborg, Sweden, a
corporation of Sweden

Filed Sept. 6, 1966, Ser. No. 3,743

Term of patent 14 years

(Cl. D26—1)

FIG. 1.

FIG. 2.

FIG. 3.

FIG. 1 is a perspective view of the portable welding transformer,

FIG. 2 is a side view, and

FIG. 3 is an end view of the transformer.

The dominant features reside in the solid line portions.
I claim:

The ornamental design for a portable welding transformer, as shown and described.
